CLAIM

The ornamental design for a straw as shown and described.

DESCRIPTION

FIG. 1 is a first perspective view of a straw showing our new design;

FIG. 2 is a second perspective view thereof;

FIG. 3 is a first side view thereof;

FIG. 4 is a second side view thereof;

FIG. 5 is a third side view thereof;

FIG. 6 is a fourth side thereof;

FIG. 7 is a top view thereof;

FIG. 8 is a bottom view thereof;

FIG. 9 is a perspective view thereof in a first alternate position of use in a container lid environment; and,

FIG. 10 is a perspective view thereof in a second alternate position of use in a container lid environment.

The broken lines are shown for the purpose of illustrating both parts of the article, as well as environmental subject matter of an exemplary container lid. None of the broken lines form part of the claimed design.

The straw includes symbolic break in the length. The appearance of any portion between the break lines forms no part of the claimed design.
